UNITED STATES PATENT OFFICE

1,929,041

MILK BOTTLE CRATE

Charles A. Snyder, Willow Grove, Pa.

Application October 7, 1931. Serial No. 567,496

3 Claims. (Cl. 217—19)

My invention relates to new and useful improvements in a milk bottle crate, and has for one of its objects to construct such a crate of two units which when placed together form a complete crate including bottle separators and spacers or partitions, bottle supports, and shields or protectors for the lower edges of the body sides and ends or the lowermost slats of the body walls.

10 Another object of the invention is to provide a crate of the character described, so constructed that a combined bottom and protector for the body, or a combined bottom, interior structure and a protector for the body will be a unitary device for application to a crate or box body which is produced as an independent or separate unit, the two units to be finally fastened together for completion of the crate.

Another object of the invention is to provide a 20 simple and effective means for connecting the separators and spacers to each other.

Another object of the invention is to produce a corner post of unique formation.

A further object of my invention is to provide 25 shields or protectors for the lower edges of the crate body which will fully protect the same from damage and provide a smooth hard surface for sliding the crate over floors, platforms, sliding boards and the like.

30 A still further object of the present invention is to produce the lower end of each corner post with an offset to provide a chamber for the ends of contiguous protectors or shields and leave room for entrance of a lug on the post of another crate when said crates are stacked on top of each other.

With these and other ends in view, this invention consists in the details of construction and combination of elements hereinafter set forth 40 and then specifically designated by the claims.

In order that those skilled in the art to which this invention appertains may understand how to make and use the same, I will describe its construction in detail, referring by numerals to the accompanying drawings forming a part of this application, in which:

Fig. 1 is a bottom plan view of a milk bottle crate constructed in accordance with one form 50 of my invention.

Fig. 2 is a side elevation thereof.

Fig. 3 is a perspective view looking on the top thereof of the bottom unit as it appears when removed from the body and one of the shields or protectors being partly broken away.

Fig. 4 is a perspective view of one of the sepa-

rators prior to the assembly of spacers thereon.

Fig. 5 is a fragmentary side elevation or edge view of one of the spacers.

Fig. 6 is a fragmentary sectional view at the point of connection of one of the spacers with a 60 separator.

Fig. 7 is an upper end view of one of the corner posts on an enlarged scale.

Fig. 8 is a side elevation thereof.

Fig. 9 is a bottom end view of the same. 65

Fig. 10 is a fragmentary elevation looking toward one of the side edges.

Fig. 11 is a perspective view on a reduced scale of the protectors or shields for the bottom edges of the body walls illustrating a way to form said 70 parts as a frame.

Fig. 12 is a perspective view of another form of separator.

Fig. 13 is a perspective view looking at the bottom of a milk bottle crate showing a modified 75 form of bottom unit.

Fig. 14 is an enlarged side elevation of one of the ribs used in forming the bottom unit illustrated in Fig. 13.

Fig. 15 is a top plan view of Fig. 14. 80

Fig. 16 is a side elevation on a reduced scale of a duplex rib structure.

In carrying out my invention as herein embodied, 20 represents the corner posts produced in the general configuration of angle irons with 85 spacing ribs 21 formed on their outer surfaces between which the slats 22 forming the sides 23 and ends 24 of the box or crate body may be positioned and then held by suitable fastening means passing through the ends of the slats and 90 holes 25 in the sides of said corner posts.

The slats next to the uppermost ones either at the sides, ends or both may be eliminated as shown in Fig. 2, in order that the uppermost slats of the body walls may be used as hand holds for 95 lifting the crate, or said slats may be installed and some of them provided with notched out portions to produce the hand holds.

It is to be understood that many of the features of my invention may be utilized even where the crate body is made of solid wood or metal walls. In the latter case, the corner posts would be formed without the spacing ribs 21.

The lower end of each corner post is provided with an outwardly projecting offset 26 to form a 105 chamber 27 for a purpose to be presently described, and incidentally, said offset produces a shoulder 28 which may or may not be utilized for a special purpose. The upper end of each corner post is provided with a guide lug 29 for 110

the purpose described in my application filed March 24, 1931, Serial No. 524,812.

The parts thus far described are only the ones used in making up the crate body unit and consist principally of the four corner posts and the end and side walls and where the latter are made up of slats as shown herein, said slats are positioned between the spacing ribs 21 and are thus properly spaced so that it becomes unnecessary for a working man to make measurements for spacing purposes so that considerable time is saved in constructing a crate and in addition each slat is supported by the spacing ribs along the top and bottom edges at both ends in addition to the support derived from the attaching means. The attaching means may be in the form of rivets 30 and they also pass through the corner plates 31 superimposed on the exterior corners of the body. Due to the offset 26 in the corner posts, the lowermost slats of the side and end walls are thinner than the others so that the exterior surfaces of all the slats will be flushed.

The bottom unit illustrated in Fig. 3, includes side and end shields or protectors 32 and 33 respectively, and when in place prevent the lower edges of the body sides and ends or the lower edges of the lowermost slats of the sides and ends of the crate body against damage from contact with other objects, such as other crates, parts of wagons or cars and hard floors.

The protectors are in the general form of angle irons and may be actually produced from angle irons with the ends of the outwardly projecting flanges cut away to provide the apertures 34 which will register with the lowermost spacing ribs 21 of coacting corner posts and the formation of said apertures leaves extensions 35 at the ends of the upstanding flanges so as to fit the interior corners of coacting corner posts as shown in Fig. 1, and in order to have the faces of the protectors in engagement with the coacting inner surfaces of the side and end walls of the crate body, said extensions 35 may be bent out of line with the balance of the upstanding flanges in order to fit around the coacting walls of the corner posts and so that the surfaces of the upstanding flanges of the protectors which contact the body walls will be flushed with the outer surfaces of the corner post walls.

The protectors are fastened by the same attaching means 30 used in securing the body walls of the corner posts for which reason the lowermost slats of a slatted crate body are left unfastened until the bottom unit is placed in position. It is not imperative that the protectors be secured in place by the same fastening means utilized for attaching the body walls to the corner posts but an extra set of holes could be provided for fastening means for the protectors.

The side and end protectors may be made separately from each other or they may be formed or produced as a single protector frame 36 as shown in Fig. 11, but since all of the parts are the same, identical reference numerals will be used.

It might be well to state at this time that wherever possible without sacrificing strength, the parts may be cut away to reduce the weight of the structure and in this respect much of the upstanding flanges of the side protectors may be eliminated, leaving only sufficient material for fastening the parts together.

Between the end protectors 33 are strung bottle supporting wires 37 and on these may be mounted separators 38 produced from sheet material

and having their ends bent out at right angles to the main parts to provide flanges by which they may, if found desirable be fastened to the side protectors 32 as well as to the sides of the crate body after the bottom unit has been assembled in said crate body.

The separators divide the interior of the crate transversely into a number of compartments and said compartments are subdivided by spaces 39 which are preferably arranged in pairs with the elements of each pair spaced vertically and said elements of each pair of spacers may be connected together at one end as shown in Fig. 3, although it will be obvious that said elements might be separate from each other, so that both ends of each spacer or spacer element will be alike.

The spacers and separators may be connected together in any suitable manner but in Figs. 3 to 6 inclusive, I have shown the separators as having sections partially cut therefrom and bent out to form clips 40 and provide apertures 41 through which the spacers 39 are projected endwise. Each spacer has side flanges 42 provided with notches 43 which register with edges of the apertures 41 after which the clips 40 are bent in to hold the spacers against accidental displacement.

The apertures 41 are of sufficient size to permit spacers to pass therethrough until such time as the notches 43 align with the panel portions of the separators but said apertures will then be closed by the clips 40 and will prevent vertical movement of the spacers and the latter being within the apertures 41 horizontal movement is prevented, and due to the registration of the notches with the panel portions said spacers cannot move longitudinally.

Upon assembly of the bottom unit in the body unit, some or all of the separators can be fastened to the body walls and some parts of the spacers can be fastened to the walls of the crate body.

Assuming that a body unit is made up complete and likewise a bottom unit such as shown in Fig. 3, then to complete a crate it is only necessary to insert the bottom unit in the body unit and fasten the ends of the protectors to the corner posts after which the crate is ready for use. As before stated some of the other parts can be fastened together and to the body unit if found desirable.

In lieu of the separators previously described, any other suitable style can be used and therefore I have illustrated one of another form in Fig. 12, which is designated by the numeral 44 and in such separator a number of lips 45 which are produced by partially cutting sections from the separator panel and bending them out at right angles so that spacers may be superimposed thereon and fastened by securing means passing through the spacers and said lips. The spacers in all instances may be similar to those heretofore described and illustrated in the drawings or they may be flat strips, either straight or having curved bent up or cut out portions or wires.

Where the separators are of sufficient height to reach from a point below the bottle supports to a point above or corresponding with the uppermost spacers, the lower rail or bottom part of the separator is provided with holes 46 for the passage of the bottle supports, said holes being round where wire supports are used or of any other shape corresponding to the cross sectional contour of the body supports.

In Fig. 13, I have illustrated a modified form of bottle crate in which the separating and spac-

150

ing means are made from wires 47 and arranged crosswise of each other and secured in the end and side walls of the body unit so that the bottom unit need only consist of the protectors, the bottle supports and suitable strengthening ribs for said bottle supports intermediate their ends.

For this purpose, I have illustrated in Figs. 13, 14 and 15, ribs 48 produced from flat strips of metal having their ends bent and turned so that the faces of the ends are at right angles to the faces of the intermediate parts as well as said ends being at right angles to said intermediate parts.

These ribs are connected with the bottle supports and the latter are connected to the end protectors and, if found desirable, the ends of the ribs 48 may be fastened to the side protectors.

By forming the ribs as a duplex element as shown in Fig. 16 and designated by the numeral 49, the upper bar may be utilized as a support for the spacers.

When the bottom unit is assembled in the body unit, the end extensions of the protectors will occupy the chambers 27 in the lower ends of the corner posts and the inner surfaces of said end extensions will be flushed with the inner surfaces of the upper parts of the corner posts so that said end extensions will not interfere with entrance of the guide lugs 29 into the lower ends of the

corner posts when the crates are stacked on top of each other.

Of course I do not wish to be limited to the exact details of construction as herein shown, as these may be varied within the limits of the appended claims without departing from the spirit of my invention.

Having thus fully described my invention, what I claim as new and useful is:—

1. A crate comprising a body unit including corner posts and a bottom unit including protectors for the lower edges of the crate walls and means for securing the protectors to the corner posts for securing the bottom unit in place. 85

2. A milk bottle crate consisting of a body unit including corner posts and a bottom unit secured to the corner posts including bottle supporting means and means to keep the bottles separated from each other. 90

3. A milk bottle crate, comprising corner posts having the lower ends offset to provide chambers, side and end walls secured to said corner posts, angular protectors disposed on the inside and under the lower edges of the crate walls, the ends of said protectors being bent out of line and positioned in the chambers in the lower ends of the corner posts and means to secure the ends of the protectors to said corner posts. 95 100
